UNITED STATES PATENT OFFICE.

ROBERT A. OSBURN, OF BIRMINGHAM, ALABAMA.

CONVERTIBLE SOCKET WRENCH.

Application filed July 13, 1921. Serial No. 484,310.

To all whom it may concern:

Be it known that I, ROBERT A. OSBURN, a citizen of the United States of America, residing at Birmingham, in the county of Jefferson and State of Alabama, have invented certain new and useful Improvements in Convertible Socket Wrenches, of which the following is a specification.

My invention relates to a socket wrench which is convertible into all of the different wrench sizes and shapes needed for tightening or removing the various nuts and bolts used on an automobile or other piece of machinery.

15 In its essence my invention comprises a plurality of sleeve wrench sockets each having different sized openings and all adapted to be inter-connected by cranks having different sized lugs or tenons adapted to fit in either end of the socket sleeves.

By the arrangement described, the wrench can be adapted to form a brace or a variety of cranks of different sizes, lengths and shape so that the end sleeve socket can be applied to the work in places most difficult of access.

30 My invention is also adapted to the formation of a crank for automobile engines by designing an interchangeable wrench sleeve having one end adapted to couple to the crank shaft of the engine.

35 My invention also comprises the novel features of construction and arrangements of parts, which in their preferred embodiments only are illustrated in the accompanying drawings, which form a part of this specification, and in which:—

40 Fig. 1 is a perspective view of my convertible socket wrench, the dotted lines indicating a change in position of parts to increase the leverage of the wrench.

Figs. 2 and 3 are detail views illustrating the cranks with single socket wrenches reversely applied thereto.

45 Fig. 4 is a detail view of the special crank sleeve, shown partly in section to illustrate its attachment to the double lug on the crank.

50 Fig. 5 is a detail view of the intermediate socket wrench sleeve showing a grip bushing or sleeve sprung thereon in quarter section.

Similar reference numerals refer to similar parts throughout the drawings.

55 My invention as illustrated comprises three sleeve socket wrenches 1, 2 and 3 which are

of the same general character, and each of which is provided with wrench sockets at each end, the wrench socket at one end of each sleeve being larger than that of the other at such sleeve. As shown the sockets in the sleeve 1 are both larger than either socket in the sleeve 2, and in like manner the sockets in the sleeve 2 are both larger than the sockets in the sleeve 3. As shown 65 each sleeve is enlarged about half of its length. The large and small sockets in the sleeve 1 are respectively designated A and B and the large and small sockets of sleeve 2 are designated C and D, and the large and 70 small sockets of the sleeve 3 are designated E and F, respectively. The sleeves are adapted to be connected together by cranks 4 and 5, which are substantially similar and are provided at each end with double lugs 75 adapted to fit the socket at either end of a sleeve. The crank 1 has at one end two lugs A' and B', A' being adapted to fit the socket A and B' to fit the socket B. At its other end the crank 4 has lugs C' and D' adapted, 80 respectively, to fit the sockets C and D of the sleeve 2. The crank 5 has at one end lugs C' and D' which are similar to the lugs C' and D' on crank 4, and thus are adapted to fit either desired socket of the sleeve 2. At 85 its other end the crank 5 has two lugs E' and F' adapted respectively to fit the sockets E and F of the sleeve 3.

In addition to the sleeves described I may, if desired, provide the wrench with an additional sleeve 6 provided at one end with a socket A adapted to fit the lug A' and having its other end 7 provided with notches 8 or other equivalent means for engaging the crank shaft of the type of engine to be 90 worked. If desired the sleeve 6 may be provided with a set screw 9 to hold it rigid on the crank 4. It will be obvious that the tool, as shown in Fig. 1, may be changed by applying the socket A to the lug A', thereby exposing the socket B to receive the nut, or in like manner the sleeve 3 can be reversed as indicated in Fig. 3. Both of these changes leave the apparatus assembled as a brace.

If it is desired to work nuts of intermediate sizes between those for which the sleeves 1 and 3 are suited, the crank 4 or 5, as desired, is selected and the sleeve 2 is mounted thereon to present either end socket to the work. By changing the position of 110 the crank 5 to that shown in dotted lines, Fig. 1, I convert the tool, as shown, from a

brace to a crank which is adapted for handling work in difficult places. Obviously the crank 4 may be used alone with the sleeve 1 or the crank 5 with the sleeve 3, and in like manner any one of the sleeves can be worked as a crank wrench. Where desired, the sleeve 6 may be applied to the brace or to the crank 4 and used to crank the car, or, if desired, the sleeve 2 may be left applied to either 10 crank that is in service when working sleeve 1 or 3 to afford a better handle or grip. One advantage of my double lug is that when working with the larger lug in one of the sleeve sockets in difficult places I can, by 15 partly withdrawing the crank to disengage only the larger lug and then turning the crank back and reinserting it in the socket, work the wrench like a ratchet wrench, the smaller lug forming a guide for this purpose. This ratchet action is of peculiar advantage in many places difficult of access.

The tool when not in use can all be taken apart and assembled in a very compact space and obviously the cranks and sleeves can be 25 designed to suit any class of work for which the tool is intended.

In order to provide the brace and crank wrench forms with a handle which will turn freely in the hand, I show the intermediate sleeve 2 somewhat reduced at its intermediate portion so that a spring bushing of grip sleeve 10 is adapted to be sprung over the sleeve and to form a rotatable grip thereon which will function with either crank 30 or with the two cranks when the wrench is operated as a brace wrench. This rotatable grip may be applied in any desired manner.

This invention is not intended to be restricted in scope to the specific embodiments shown, but contemplates such modifications as come within the spirit and scope of the claims.

Having thus described my invention, what I claim as new and desire to secure by Letters Patent, is:—

1. In a convertible socket wrench comprising a crank having at each end a lug reduced to form a pair of different sized socket tenons, and sleeves formed with different sized wrench sockets at their ends adapted to fit corresponding sized socket tenons on their respective lugs.

2. A wrench comprising three sleeves having wrench sockets at their ends, and a pair 55 of cranks having lugs substantially at right angles to their ends and adapted to interfit with the sleeve sockets to form an assembled tool.

3. A convertible socket wrench comprising

two cranks, each crank having at a corresponding end a similar lug stepped to form a pair of different sized socket tenons, and each crank having at its other end a lug formed to provide a pair of different sized socket tenons which are of different size on each crank, and reversible sleeves having at their ends sockets to fit either of their respective pair of socket tenons.

4. A wrench comprising an intermediate and two end sleeve socket wrenches, a pair of cranks having end lugs adapted to interfit with the sockets in the adjacent ends of the sleeves to form a brace wrench, and a grip sleeve rotatably mounted on the intermediate socket sleeve.

5. In a convertible socket wrench, a series of sleeves having in their end sockets which graduate in size, and cranks having lugs with two socket tenons on their ends which also graduate in size to correspond with the sizes of the sleeve sockets and which cranks are adapted to connect the sleeves, as and for the purposes described.

6. A wrench comprising an intermediate brace grip member, a pair of cranks, each having means at one end to engage said grip member, and each having at the other end a double lug, said lugs being of different sizes, and reversible sleeve socket wrenches having end nut sockets each adapted to fit one of said lugs.

7. A wrench comprising an intermediate brace grip member, a pair of cranks, each having means at one end to engage said grip member, one crank having at one end hand grip means, and the other crank having at its other end a double lug, one larger than the other, and a reversible sleeve socket wrench having end nut sockets each of which is adapted to fit one of said lugs.

8. A convertible socket wrench comprising a pair of cranks, a brace grip member, means at one end of each crank to connect it to an end of said grip, and a hand grip and nut wrench socket respectively at the other end of said cranks.

9. A rigid crank having at one end a double tenon adapted to engage in different sized sockets of a sleeve wrench, and having at its other end means adapted to couple it to a brace grip, in combination with a reversible socket wrench having different sized nut sockets adapted to fit said double tenon.

In testimony whereof I affix my signature. 115
ROBERT A. OSBURN.
